UNITED STATES PATENT OFFICE

118,158

DESIGN FOR A COMBINATION ASHTRAY
AND COASTER OR SIMILAR ARTICLE

Henry P. C. Keuls, Pittstown, N. J.

Application October 31, 1939, Serial No. 87,956

Term of patent 7 years

To all whom it may concern:

Be it known that Henry P. C. Keuls, a citizen of Kingdom of the Netherlands and resident of the village of Pittstown, Franklin County and State of New Jersey, has invented a new, original, and ornamental Design for a Combination Ashtray and Coaster or Similar Article, of which the following is a specification, reference being had to the accompanying drawing, forming part thereof, in which

Fig. 1 is a perspective view, less than life size, of a combination ashtray and coaster or similar article, showing my new design.

Fig. 2 is a side elevational view thereof.

I claim:

The ornamental design for a combination ashtray and coaster or similar article, substantially as shown.

HENRY P. C. KEULS.
